UNITED STATES PATENT OFFICE

91,084

DESIGN FOR A COMBINATION DISH

Robert H. Pittman, Pittsburgh, Pa.

Application May 4, 1933. Serial No. 48,005

Term of patent 3½ years

To all whom it may concern:

Be it known that I, ROBERT H. PITTMAN, a citizen of the United States, residing at Pittsburgh, in the county of Allegheny and State of Pennsylvania, have invented a new, original, and ornamental Design for Combination Dish, of which the following is a specification, reference being had to the accompanying drawing, forming part thereof.

Fig. 1 is a top plan view of my combination dish; and

Fig. 2 is a side elevation of the same.

Referring to the accompanying drawing, the inside of each compartment of my combination dish is of circular form, while the outer edge of the flange of each compartment is of octagonal form of uniform configuration throughout the entire extent thereof.

I claim:

The ornamental design for a combination dish, as shown and described.

ROBERT H. PITTMAN.
